(57) **CLAIM**

The ornamental design for a hair clipper blade, as shown and described.

DESCRIPTION

FIG. 1 is a perspective view showing a new design for a hair clipper blade.

FIG. 2 is an enlarged perspective view of a portion of the hair clipper blade.

FIG. 3 is a front elevational view of the hair clipper blade.

FIG. 4 is a back elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The horizontal broken line, which connects the ends of the outermost solid contour lines in FIG. 8, illustrates the bounds of the claim and forms no part of the claimed design.
